UNITED STATES PATENT OFFICE.

EDWARD G. LAWRENCE AND ROLLAND B. BLAIR, OF MINNEAPOLIS, MINNESOTA, ASSIGNORS TO O. B. McCLINTOCK COMPANY, OF MINNEAPOLIS, MINNESOTA, A CORPORATION OF MINNESOTA.

DESIGN FOR A CASE FOR CONTAINING ELECTRICAL APPARATUS.

Application filed September 2, 1927. Serial No. 23,280. Term of patent 7 years.

To all whom it may concern:

Be it known that we, EDWARD G. LAWRENCE and ROLLAND B. BLAIR, citizens of the United States, residing at Minneapolis, in the county of Hennepin and State of Minnesota, have invented a new, original, and ornamental Design for a Case for Containing Electrical Apparatus, of which the following is a specification, reference being had to the accompanying drawing, forming part thereof.

The single view of the drawing is a perspective of a case for containing electrical apparatus, showing our new design.

The dominant feature of this invention consists in the formation of the inner border comprising two spaced horizontal rows of vertical lines, between which are two vertical rows of horizontal lines.

We claim:

The ornamental design for a case for containing electrical apparatus, as shown and described.

EDWARD G. LAWRENCE.
ROLLAND B. BLAIR.
